CIRCUIT BREAKER

Stephen S. Grady, Magnolia, N. C., assignor to
Fusoid Electric Co., Inc., a corporation of New
York

Application May 6, 1932, Serial No. 609,597
Renewed February 28, 1935

18 Claims. (Cl. 200—88)

This invention relates to electric current controlling or electric current change detecting devices in general and more especially to electric circuit breakers.

5 Among the objects of the present invention, it is aimed to provide an improved electric current controlling or change detecting device by means of which an indicator or actuator may be acted upon to indicate either a gradual abnormal increase in current or light overload or a sudden abnormal heavy increase in current or heavy overload.

10 Specifically it is an object of the present invention to provide an electric current controlling or change detecting device consisting essentially in a magnet that will not only detect a persistent light overload or a persistent light increase in current but also detect a sudden heavy overload or sudden heavy increase in current.

15 It is still another object of the present invention to provide an improved magnet consisting of a core and a bimetal coil by means of which an electric current detecting indicator may be acted upon not only when a persistent light overload or a persistent light increase in current occurs but also when a sudden heavy overload or sudden heavy increase in current occurs.

20 It is still another object of the present invention to provide an improved combined magnet and thermostat which will thermostatically effect an interruption in an electric current when a light overload or light increase in current occurs and will magnetically effect an interruption in the current when a sudden heavy overload or sudden heavy increase in current occurs.

25 The present invention also aims to provide a circuit breaking device having a casing particularly adapted for use with a group of circuit breakers, similarly encased both to conserve space and to facilitate insulation one from the other without any loss of wall space or the like.

30 These and other features, capabilities and advantages of the invention will appear from the subjoined detail description of one specific embodiment thereof illustrated in the accompanying drawings, in which

35 Figure 1 is a longitudinal section of a circuit breaker in circuit making position made according to the present invention and illustrating the improved electric current change detecting elements;

40 Fig. 2 is a fragmental longitudinal section showing the circuit breaker in circuit breaking position;

45 Fig. 3 is a plan view of the circuit breaker

with the cover removed on a smaller scale than that illustrated in Fig. 1;

Fig. 4 is a section on the line 4—4 of Fig. 1;

Fig. 5 is a section on the line 5—5 of Fig. 1;

Fig. 6 is a section on the line 6—6 of Fig. 1;

Fig. 7 is a perspective of the actuating elements of the circuit breaker and of the main elements constituting the electric current change sensing device; and

Fig. 8 is a perspective of a detail of the circuit breaker appurtenant to the tripping device of the circuit breaker.

In the embodiment illustrated, there is provided a casing 1 composed of some suitable insulating material such as bakelite or the like. 15 This casing in the present instance consists of end walls 2 and 3, side walls 4 and 5 and a bottom wall 6.

The end wall 2, see particularly Fig. 1, preferably is recessed at 7 below its upper edge, which 20 recess will register with the adjoining recess 7 of an adjacent casing 1 to permit the insertion of an insulated sheet or plate 8 to facilitate insulating the terminals in the end walls 2 now to be described.

25 The bottom wall 6 of the casing 1, see particularly Fig. 1, is provided with a recess 9 adjacent to the end wall 2. This recess 9 is of considerable advantage when a plurality of these casings are grouped adjacent to one another and 30 as illustrated in Fig. 1, and a common bus bar 10 is connected to the aligned terminals of the adjacent casings.

The drawings illustrate a circuit breaker although it is obvious that the main elements of 35 this device may be effectively used in any electrical current change detecting device or current controlling device.

When these elements are used in a circuit breaker and casing 1 aforesaid is used, then preferably a conductor plate 11 is connected to the lower face of the casing in the recess 9, which conductor 11 has a U-shaped end portion 12, the upper face of the upper flange of which is disposed flush with the lower face 14 of the inner 45 face of the wall 6 adjacent to the side wall 2 and such flange 13 completely encloses the discharge end of the opening 15 formed in the bottom wall 6 communicating with the recess 9. Forwardly of the opening 15, the bottom wall 6 50 is preferably chambered as at 16, which chambered portion 16 is further depressed at its rear end as at 17. In circuit making position, the upper face of the conductor 11 constituting one terminal of this device contacts with the shoe 18 55

at the rear end of the spring 19, which spring is connected to the plate 20, the extensions 21 and 22 of which, see Fig. 8, are preferably secured in place to the bottom wall 6 forwardly of the recess 17 by the screws 23 and 24.

This shoe is further connected by the flexible conductor 25 with the bimetal coil 26. This bimetal coil in the present instance is composed of adjacent layers of invar steel and brass and rolled up into a coil to form for the purpose of one part of this invention, the coil of a magnet, the inner end of which coil 26 has secured thereto the soft iron core 27. This core 27 and inner end of the coil 26 is preferably connected to the lateral extension 28 of the plate 29, which see Fig. 3, has its end disposed in the recess 30 where it is preferably anchored in place by the screw 31.

The end portion 32 of the plate 29 is connected to the main conductor 33 by the terminal screw 34. The extension 28 of the conductor 29 preferably has its free end diminished as indicated at 35 to ride in the recess 36 formed in the side wall 5 of the casing.

The core 27 of the magnet, see particularly Fig. 3, has its ends extending beyond the coil 26. The free ends of the core 27 are so exposed to facilitate cooperation with the wings 37 and 38 of the bracket 39, such wings 37 and 38 extending upwardly to either side of the coil 26 and the bracket 39 itself being pivoted by means of the pivot extensions 40 and 41 being journaled in the openings formed in the upwardly extending flanges 42 and 43 of the plate 44 which is secured upwardly to the bottom wall 6 by means of the screw 45.

The rear end of the plate 44 is preferably provided with a forwardly extending projection 46 to form an abutment for the spring 47 which engages the lower face of the arm 48 normally to urge the arm 48 upwardly about the pivot points 40 and 41 and thereby to urge the wings 37 and 38 away from the core 27.

The plate 44 of course forms a limiting stop for the bracket 39. The arm 48 supplies some of the main elements for anchoring the circuit breaking device in circuit making position when disposed in its raised position due to the spring 47. On the other hand when rocked downwardly by the rearward movement of the wings 37 and 38, the circuit breaker will be released to snap into circuit breaking position.

Before proceeding to a detailed description of the circuit breaking device, it may be of advantage here to point out that when a light overload or light increase in current, and preferably a persistent or sustained light overload occurs, the current passing from the terminal 11 to the terminal 29, the coil 26 will heat up and thereby thermostatically actuate the bracket 39 by causing the extensions 49 and 50 of the outer end of the coil 26, see particularly Fig. 7 to rise into engagement with the wings 37 and 38 to move them rearwardly and thereby to depress the arm 48.

On the other hand when a sudden heavy overload or sudden increase in current occurs, the magnetic force created by the magnet and particularly the magnetic attraction set up in the soft iron core 27 will attract the wings 37 and 38 of the bracket 39 again to depress the arm 48. It is of course to be understood that the bracket 39 is composed of a current conducting metal, preferably a conductive metal.

In the present instance, the terminal plate 11, see particularly Fig. 1, is connected to the main

conductor by the terminal screw 52 to which on the other hand the bus bar 10 may be connected instead of the main conductor when a group of these devices are disposed adjacent to one another.

The circuit breaking device consists essentially of an interposer composed of a plate 53 composed of some suitable insulating material such for instance as bakelite or the like. The rear end 54 of the plate 53 is flared as shown, the forward end of which is provided with two lateral arms 55 and 56, at the extreme forward ends of which are provided the projections 57 and 58 to receive the springs 59 and 60 which are preferably disposed in arcuate recesses formed in the casing 1, see particularly Fig. 6, with their forward ends abutting against the rear faces of the bosses 61 and 62 respectively.

The plate 53 in width preferably extends across the entire expanse of the interior of the casing 20 from one side wall 4 to the other side wall 5 and is mounted to slide on the face 14 and the shoulders 63 and 64 forwardly of the face 14.

It would also appear from the foregoing that when the interposer 53 is in circuit breaking position, that illustrated in Fig. 2, it will completely cover the upper face of the flange 13 so that in circuit breaking position the current cannot possibly arc around the interposer from the shoe 18 to the flange 13.

The interposer 53 is provided with downwardly extending projections 65 and 66 preferably formed on a metal plate 67 secured to the interposer plate 53. These projections 65 and 66 are adapted to cooperate with the forward face or shoulder 68 of the crosspiece 69 formed on the bracket 39 and the forward end or shoulder formed by the finger 70 extending down from the bracket 39, the projection 66 engaging the finger 70 and the projection 65 engaging the shoulder 68 in circuit making position, that illustrated in Fig. 1.

On the other hand when the arm 48 of the bracket 39 is depressed downwardly against the tension of the spring 47, due to the rearward movement of the wings 37 and 38 as aforesaid when an abnormal or changed current condition arises, the finger 70 and shoulder 68 will move out of engagement with the projections 66 and 65 respectively of the interposer 53 and permit the springs 59 and 60 to snap the interposer forwardly into circuit breaking position where, see Fig. 2, the plate 53 will slide under the shoe 18 and urge it upwardly out of contact with the flange 13 against the tension of the spring 19.

For resetting the interposer 53 into circuit making position, the handle 71 is provided which is preferably composed of bakelite or the like or other suitable insulating material and in the present instance has an extension or finger engaging portion 72, an enlarged arcuate portion 73 to the inner end of which arcuate portion, there is secured a metal bracket 74 having trunnions 75 and 76 formed on lateral extensions thereof journaled in the upwardly extending ends of the lateral extensions 77 and 78 of the plate 79 from which the extensions 21 and 22 extend.

The plate 79 preferably at the lower ends of the wings 77 and 78 is provided with the projections 80 and 81 to rest in the recesses 82 and 83 of the casing 1.

This handle 71 is preferably provided with a coil spring 84 for normally urging the extension 72 in a forward direction, that illustrated in 75

Fig. 2, the spring 84 being tensed between the plate 14 and the abutment 85.

To the plate 14, there is pivotally connected the lever 86, which see Figs. 5 and 8, has a projection 87 adapted to ride under a portion of the spring 18. The lever 86 is provided with a spring 88 normally to urge the lever 86 so that its projection 87 will tend to move under the adjacent portion of the spring 18. The spring 18, see particularly Fig. 8, is provided with an opening 89 to permit the lever 86 to extend down through it.

The upper face of the projection 87 forms an oblique angle with the shortest radius to it from the center of the arm 86.

This oblique angular relation of the upper face of the projection 87 to the axis of the arm 86 is of importance in the action of this device and will be hereinafter described.

After the interposer 53 has been moved into circuit breaking position, that illustrated in Fig. 2, it will only be necessary to engage the extension 72 of the lever 71 and move it rearwardly into the position illustrated in Fig. 1 when its lever 86, extending as it does through the spring 18 and into engagement with the shoulder 90 of the plate 61, will thereby move forwardly with it the interposer plate 53 until its projections 65 and 66 pass the shoulders 68 and 70 of the bracket 38 when the interposer plate 53 will again be locked in circuit breaking position by the bracket 39. After the lever 71 has so moved the interposer plate 53 into circuit making position, it will then be necessary for its lever 86 to be moved out of the path of movement of the shoulder 90 in order to permit the interposer plate 53 subsequently to be urged into circuit breaking position without interference with the lever 86 and in addition thereto it will be desirable to anchor the lever 71 against movement in such circuit making position.

In order that the lever 86 may clear the shoulder 90 after moving the interposer 53 into circuit making position, it will be found that the following action takes place.

In circuit breaking position, the projection 87 due to the tension of the spring 88 will ride under the spring 18 whereupon during the forward movement of the interposer 53, the frictional contact of the arm 86 with the shoulder 90 will so anchor the lever 86 that it will not move about its pivot but positively return the interposer 53. However, after the interposer has been returned and anchored into position by its cooperation with the bracket 39 and the release of the lever 71 takes place so that the frictional contact of the arm 86 with the shoulder 90 will have been broken, then the downward urge of the spring 18 on the upper face of the projection 87 will act to cam the lever 86 out of engagement with the spring 18 against the tension of the spring 88.

At this time, however, it will be desirable as aforesaid to anchor the lever against movement in circuit making position. For this purpose, there is provided the lever 91 pivotally connected to the wing 71 of the plate 18. This lever has a lateral extension 92 and a downwardly extending shoulder forming portion 93. The shoulder forming portion 93 will engage the lateral extension 94 of the plate 14 when in circuit making position and thereby anchor the lever 71 in circuit making position. The lateral extension 92, see particularly Figs. 2 and 8, is disposed adjacent to the raised portion 95 of the spring 18 and consequently when the spring 18 is raised during the circuit breaking action, this exten-

sion 95 will engage the lateral extension 92 to raise the lever 91 against the tension of the spring 88 and thereby permit the spring 88 to cause the plate 14 to pivot about its axis with the upper extension 72 moving forwardly. The abutment 85 of the spring 88 as will clearly appear from Fig. 8 is in the present instance, an integral part of the lever 86.

From the foregoing, it will thus appear that the spring 88 serves not only to maintain the rear arm of the lever 91 in engagement with the lateral extension 94 of the plate 14 but also to exercise an angular tension on the plate 14.

From the foregoing, it will thus appear that when the magnet consisting of the coil 26 and core 27 is inserted in the conductors of an electric circuit, it may control a circuit breaker to protect the line of which the conductor or bus bar 10 forms a part with the conductor 33 as specifically illustrated in Fig. 1, or else these elements may form the main actuating elements of a current change sensing or current controlling device in which either when an abnormal current or a different current is passed through the system, either the core 27 will cooperate with an actuator, such as the bracket 39 or the thermostatic action of the coil 26 will cooperate to actuate an actuator such as the bracket 39 either to indicate such change or abnormal condition or else to initiate a change to overcome or bring about a return to normal.

The casing 1 is preferably provided with a suitable cover of insulating material such as the cover 96 which is preferably connected to the casing by the screws 97 and 98 shown in section in Fig. 4 which pass through the openings 99 and 100 of the casing 1, shown in Fig. 3.

The cover preferably has an opening 101 with arcuate flanges 102 to either side thereof, the ends 103 and 104 of which slot 101 are preferably substantially radial to the axis of the lever 71, the enlarged portion 73 conforming to the inner arc of the flanges 102 so as to substantially shut off access to the interior of the casing 1 when the cover is closed and to prevent the discharge of any electric arc flashes.

It is of course obvious that the bracket 39 will not return into position where it will lock the interposer 53 until the condition causing the overload has been removed and the overload relieved, even though the resetting handle 71 is operated to actuate the interposer into circuit making position and that the automatic return of the interposer into circuit breaking position as soon as the handle is released due to this action of the bracket 39 will in turn actuate the trip for the handle to permit it to be rotated into circuit breaking position.

This action of the bracket 39 is of course due to the fact that during the overload the wing portions will be maintained in tilted position when the lower portion 48 will be maintained in depressed position where it cannot anchor the interposer in circuit making position.

To facilitate adjusting the position of the projections 49 and 50 at the end of the bimetal coil 26 either nearer or farther away from the core 27 due to the moldability of the copper plate 28 which is an integral part of the plate 26 if the diminished neck portion 107 between the plate portions 26 and 28 is engaged by a tool such as the device 105 having the jaw 106, the plate 28 may be readily bent in one direction or the other either to move the projections 49 and 50 nearer to the wings 37 and 38 or farther away from the 75

same, according to the adjustment required.

It is obvious that various changes and modifications may be made to the details of construction without departing from the general spirit of the invention as set forth in the appended claims.

I claim:

1. An electric current change sensing device consisting of a magnetic device connected to the conductors of an electric circuit to form a part of an electric circuit, said magnetic device comprising a bimetallic coil, and a core connected to the inner end of said coil, the outer end of the coil and said core forming the terminals of said magnetic device, and an actuator normally spaced from said core and forming a part of a current controlling device operatively associated with said magnetic device to be actuated toward said core either by the thermostatic action of said coil or the magnetic action of said core.

2. In an electric controlling device, the combination with an actuator, of a magnetic device forming part of the electric circuit to be controlled comprising a bimetallic coil, and a core connected to the inner end of said coil, the outer end of the coil and said core forming the terminals of said magnetic device, said actuator being operatively associated with said magnetic device to be actuated toward said core either by the thermostatic action of said coil or the magnetic action of said core.

3. In an electric current controlling device, the combination with a pivotally mounted metallic actuator, of a magnetic device forming part of the electric circuit to be controlled comprising a bimetallic coil, and a core secured to the inner end of said coil, said coil having an abutment at its outer end, one arm of said actuator being disposed between said abutment and said core to be actuated either by said abutment during the thermostatic action of said coil or said core during the magnetic action of said core.

4. In an electric current controlling device, the combination with a pivotally mounted metallic actuator, of a magnetic device forming part of the electric circuit to be controlled comprising a bimetallic coil having an abutment at its outer end, and a core at its inner end, one arm of said actuator being disposed between said abutment and said core to be actuated either by the magnetic attraction of said core or by engagement with said abutment during the thermostatic action of said coil.

5. In an electric current controlling device, the combination with an actuator, of a magnetic device forming part of the electric circuit to be controlled comprising a thermostatic coil having an abutment at its outer end and having a core at its inner end, said actuator being operatively disposed between said abutment and said core to be operated by either one or the other or both.

6. The combination with two terminals of a main circuit, of a circuit breaker connected to said terminals, said circuit breaker comprising a fixed contact connected to one of said terminals, a magnetic device connected to the other of said terminals, a movable contact connected to said magnetic device, an interposer for deflecting said movable contact out of engagement with said fixed contact, said magnetic device comprising a thermostatic coil having an abutment at its outer end and a coil at its inner end, means for normally urging said interposer into circuit breaking position, and an anchoring device for anchoring said interposer in circuit making

position, said anchoring device being operatively associated with said abutment and core to be actuated to release said interposer either by the magnetic action of the core with a sudden heavy overload or by the movement of said abutment during the thermostatic action of said coil with a persistent light overload.

7. The combination with two terminals of a main circuit, of a circuit breaker connected to said terminals, said circuit breaker comprising a fixed contact connected to one of said terminals, a magnetic device connected to the other of said terminals, a second contact connected to said magnetic device, a spring for normally maintaining said second contact in engagement with said fixed contact, an interposer, means for actuating said interposer to deflect said second contact out of engagement with said fixed contact to interrupt the circuit, and an anchoring device for anchoring said interposer in circuit making position, said magnetic device having a thermostatic coil with an abutment at one end thereof and a core at the other end thereof in operative association with said anchoring device to actuate the same upon a change in current in turn to release said interposer.

8. The combination with two terminals of a main circuit, of a circuit breaker connected to said terminals, said circuit breaker comprising a fixed contact connected to one of said terminals, an electromagnetic device connected to the other of said terminals, a second contact connected to said electromagnetic device and normally engaging said fixed contact, an interposer, means for actuating said interposer to deflect said second contact out of engagement with said fixed contact, and a pivotally mounted bracket having one arm normally anchoring said interposer in circuit making position, said electromagnetic device comprising a bimetallic coil having an abutment at one end and a core at its inner end, the other arm of said bracket being disposed between said abutment and said core in position to be actuated by the magnetic action of said core during a heavy overload and to be actuated by said abutment during a persistent light overload in turn to release said interposer.

9. The combination with two terminals of a main circuit, of a circuit breaker connected to said terminals, said circuit breaker comprising a fixed contact connected to one of said terminals, an electromagnetic device having a movable coil connected to the other of said terminals, a second contact connected to said electromagnetic device and normally engaging said fixed contact, an interposer, means for actuating said interposer to deflect said second contact out of engagement with said fixed contact, an anchoring device actuatable both by the movement of said coil and the magnetic influence exercised by said coil when energized for normally anchoring said interposer in circuit making position, and a resetting device operatively connected to said interposer to reset the same in circuit making position.

10. The combination with two terminals of a main circuit, of a circuit breaker connected to said terminals, said circuit breaker comprising a fixed contact connected to one of said terminals, an electromagnetic device connected to the other of said terminals, a second contact connected to said electromagnetic device and normally engaging said fixed contact, an interposer, means for actuating said interposer to deflect said second contact out of engagement with said fixed contact, an anchoring device controlled by said elec- 75

tromagnetic device for normally anchoring said interposer in circuit making position, and a resetting device comprising a pivotally mounted bracket, an arm pivotally connected to said bracket, a spring for urging said arm into engagement with said interposer, and a cam on said arm for guiding said arm out of the path of movement of said interposer after having sent the same in circuit making position.

11. The combination with two terminals of a main circuit, of a circuit breaker connected to said terminals, said circuit breaker comprising a fixed contact connected to one of said terminals, an electromagnetic device connected to the other of said terminals, a second contact connected to said electromagnetic device, a spring for normally maintaining said second contact in engagement with said fixed contact, an interposer, spring means for urging said interposer into circuit breaking position, an anchoring device normally anchoring said interposer in circuit making position and adapted to be actuated by said electromagnetic device to release said interposer, and a resetting device comprising a pivotally mounted bracket, an arm pivotally connected to said bracket, a spring for urging said arm into engagement with said interposer in circuit breaking position preparatory to resetting action, and a cam on said arm cooperating with said spring to cam said arm out of the path of movement of said interposer after having reset said interposer in circuit making position.

12. The combination with two terminals of a main circuit, of a circuit breaker connected to said terminals, said circuit breaker comprising a fixed contact connected to one of said terminals, an electromagnetic device connected to the other of said terminals, a second contact connected to said electromagnetic device, means for normally maintaining said second contact in engagement with said fixed contact in circuit making position, an interposer, spring means for actuating said interposer to deflect said second contact out of engagement with said fixed contact, a bracket pivotally mounted and having two upwardly extending wings, one to either side of said electromagnetic device, and a second arm normally anchoring said interposer in circuit making position, said electromagnetic device comprising a bimetallic coil with an abutment at one end and in front of said wings and a core at its inner end in back of said wings to facilitate actuation of said bracket either by said abutment or by said core.

13. The combination with two terminals of a main circuit, of a circuit breaker connected to said terminals, said circuit breaker comprising a fixed contact connected to one of said terminals, an electromagnetic device having a movable coil connected to the other of said terminals, a second contact connected to said electromagnetic device and normally engaging said fixed contact in circuit making position, an interposer for deflecting said second contact out of engagement with said fixed contact, an anchor for normally anchoring said interposer in circuit making position and actuatable by the movement of said coil and by the magnetic influence of said coil when energized, a resetting device adapted to return said interposer into circuit making position, and means for anchoring said resetting device in circuit making position.

14. The combination with two terminals of a main circuit, of a circuit breaker connected to said terminals, said circuit breaker comprising a fixed contact connected to one of said terminals,

an electromagnetic device connected to the other of said terminals, a second contact connected to said electromagnetic device and normally engaging said fixed contact in circuit making position, an interposer for deflecting said second contact out of engagement with said fixed contact, an anchor for normally anchoring said interposer in circuit making position and actuatable associated with said electromagnetic device, a resetting device adapted to return said interposer into circuit making position, means for anchoring said resetting device in circuit making position, and means associated with said second contact to release the anchoring means for said resetting device in case of an overload.

15. In an electric current controlling device, the combination with a pivotally mounted metallic actuator, of a magnetic device forming part of the electric circuit to be controlled comprising a bimetallic coil having an abutment at its outer end, a core at its inner end, one arm of said actuator being disposed between said abutment and said core to be actuated either by the magnetic attraction of said core or by engagement with said abutment during the thermostatic action of said coil, and a metal bracket for supporting said core and bendable to facilitate adjusting the position of said abutment relative to said bracket.

16. The combination with two terminals of a main circuit, of a circuit breaker connected to said terminals, said circuit breaker comprising a fixed contact connected to one of said terminals, a magnetic device connected to the other of said terminals, a movable contact connected to said magnetic device, an interposer for deflecting said movable contact out of engagement with said fixed contact, said magnetic device comprising a thermostatic coil having an abutment at its outer end and a core at its inner end, means for normally urging said interposer into circuit breaking position, and an anchoring device for anchoring said interposer in circuit making position, said anchoring device being operatively associated with said abutment and core to be actuated to release said interposer either by the magnetic action of the core with a sudden heavy overload or by the movement of said coil with a persistent light overload, and said anchoring device being maintained in such released position either by the magnetic attraction of said core or by the thermostatically controlled position of said abutment until the overload is removed.

17. In an electric controlling device, the combination with an actuator, of a magnetic device forming part of the electric circuit to be controlled comprising a bimetallic coil, and a core connected to the inner end of said coil, the outer end of the coil and said core forming the terminals of said magnetic device, said actuator being operatively associated with said magnetic device to be actuated toward said core by the thermostatic action of said coil.

18. In an electric controlling device, the combination with an actuator, of a magnetic device forming part of the electric circuit to be controlled comprising a bimetallic coil, and a core connected to the inner end of said coil, the outer end of the coil and said core forming the terminals of said magnetic device, said actuator being operatively associated with said magnetic device to be actuated toward said core by the magnetic action of said core.
